SIGNAL GENERATOR OR MODULATOR

John R. Shonnard, New York, N. Y., assignor to
Times Facsimile Corporation, New York, N. Y.,
a corporation of New York

Application August 15, 1946, Serial No. 690,822

3 Claims. (Cl. 250—41.5)

1

This invention relates to methods and apparatus for generating electric signals, and more particularly to a photocell modulator for telefacsimile systems, picture transmission and the like.

In general terms, the object of the invention is to provide an improved photocell modulator or modulating method for generating a modulated carrier free of any direct-current component.

Another object of the invention is to provide an improved picture scanning arrangement for facsimile systems and the like having decreased signal distortion and other advantages.

In the case of ordinary photocell modulators used in facsimile systems, the output current is a modulated carrier which is amplified before being impressed upon the line circuit by a multi-stage amplifier.

The photocell in the modulator comprises a photo-electric cathode and a spaced anode. When an external battery is connected to the cell, the magnitude of the current traversing the cell at any instant is dependent upon the instantaneous intensity of illumination of the cathode.

Thus the output of the cell is a rectified current, varying in magnitude as a function of the light variations impressed thereon. Since for the steps of amplification and transmission it is desirable to convert these variable direct-current signals into amplitude variations of an alternating current or carrier frequency, a light-chopper has been employed to interrupt the illumination of the cell periodically and thus superimpose a constant-frequency variation upon the direct-current signals. In an alternative arrangement, the cell variations have been utilized to unbalance a bridge upon which a carrier potential is impressed, and thus generate a variable-amplitude carrier controlled by the cell. In both types of modulators, prior to the instant invention, the direct-current component or bias potential of the signals is present in the output current of the modulator and is of greater magnitude than the modulated carrier. This DC component or potential produces distortion of the signals in the amplifier. It cannot be completely filtered out although some filtering is usually employed with consequent distortion of the lower frequency components and reduction of the gain or amplification factor of each stage of the amplifier. In transmission, the direct-current component of the signals also produces further distortion which

2

has been unavoidable in the systems in general use prior to the present invention.

In the preferred scanning apparatus embodying the present invention, a photocell modulator is employed having a plurality of cathodes so connected to the source of carrier current and the output circuit as to produce a modulated carrier in the output circuit which is free from the direct-current bias normally produced in the usual photocell modulator. The preferred form of the invention comprises a photocell having two oppositely connected cathodes which balance out the direct-current component of the signal resulting from the light excitation of the photocell, the cathodes being alternately operative on alternate half-cycles of the impressed carrier so that a modulated carrier current free from bias traverses the output circuit, said carrier current being modulated in amplitude in accordance with the instantaneous light excitation of the cell.

Accordingly, it is another object of the invention to provide a scanning arrangement for picture transmission capable of generating a light-modulated carrier which can be amplified and transmitted without appreciable distortion. In this manner an efficient high-gain amplifier can be employed without producing objectionable distortion of the picture signals.

Other objects and advantages of the invention will appear from the following description of the preferred embodiments thereof shown in the accompanying drawings, wherein

Fig. 1 is a circuit diagram of a photocell modulator as applied to a telefacsimile transmitter;

Fig. 2 is a perspective view illustrating the construction of the photocell shown in Fig. 1;

Fig. 3 is a detail view illustrating the use of an optical wedge in conjunction with the photocell shown in Figs. 1 and 2;

Fig. 4 is a circuit diagram of modification;

Fig. 5 is an explanatory diagram corresponding to the circuit diagram of Fig. 1 or Fig. 4;

Figs. 6 and 7 are graphs of the signal currents showing the effect of the direct current bias on the wave-shape of the signals; and

Fig. 8 is a cross-sectional view of a modified photocell that may be employed in carrying out the invention.

Referring to Fig. 1 of the drawings, the elements of a telefacsimile transmitter are shown comprising the conventional rotating drum 10 carrying the picture or copy to be transmitted; an exciter lamp 11 and condenser lens 12 for illuminating the copy being scanned by the trans-

mitter; a photocell 13 for generating a signal current modulated in accordance with the variations in shading of successive elemental areas of the copy being scanned; and an aperture plate 14 forming a part of the optical system for defining the elemental scanning area. The drum 10 is rotated at a uniform speed and at the same time moved in an axial direction so that the copy on the drum is scanned from one side to the other. It will be understood that the invention is not limited to facsimile apparatus of the character shown, but may be used in electro-optical systems generally where a modulated carrier is generated.

The present invention relates primarily to the novel connection of the photocell 13 for generating an improved modulated signal carrier and to the modulating method involved, neither the arrangement of the facsimile drum nor the photocell 13 per se nor the balancing network 15 being novel. However, as will be explained, a novel construction of photocell may be advantageously employed. In the preferred embodiment of the invention illustrated, a source 16 of alternating electromotive force is connected to the photocell 13 and network 15 in such a manner that a modulated carrier appears in the output circuit 17 which is free of direct-current bias normally generated by the light excitation of the photocell. In order to eliminate the direct-current bias, a photocell 13 having two separate photoelectric cathodes 19 is employed, said cathodes being simultaneously and equally illuminated by the controlling light beam. In this modification, the photocell 13 is also provided with two anodes 20, each mounted in front of the active surface of one of the cathodes.

A photocell which may be employed in the circuit of Fig. 1 is illustrated in Fig. 2. By way of example, the RCA #920 gas photocell is illustrated. This photocell comprises two cathodes 19 and two wire-shaped anodes 20 attached to the press 21, the electrodes being mounted in the usual transparent envelope 22 and provided with a base 23 carrying the contact pins 24. The #920 photocell is normally provided with a four-pin base with each pin connected to one of the four electrodes 19, 20. The emissive coating on the front side of the cathodes may be caesium. Other emissive materials may be employed if special light-sensitive characteristics are desired, and as will be explained hereinafter, the spacing and physical arrangement of the electrodes may be varied without departing from the spirit of the invention.

Referring again to Fig. 1, each cathode 19 of the photocell 13 is externally connected electrically to the opposite anode 20, and one cathode is connected to one terminal of the carrier source 16 and of the bridge 15. The other cathode 19 of the photocell is connected to the output circuit 17.

As explained in detail in Patent No. 2,430,095, issued November 4, 1947, to W. P. Asten, the bridge 15 comprises resistance arms 26, 27, 28, 29 and 30, the resistance 27 being in the form of an adjustable potentiometer to provide for either positive or negative recording, as desired. If the adjustable tap of the potentiometer is moved to a point on one side of the center, the bridge may be balanced (zero output current) for "black" or no illumination of the cell. With this adjustment, as white copy is scanned, the bridge becomes unbalanced to generate an output signal proportional to or dependent upon the illumination of the cell, and thereby effect "negative"

recording upon a receiver which is designed to record black on maximum signal current. On the other hand, if the adjustable tap of the potentiometer 27 is moved in the other direction, the bridge may be balanced for "white" or maximum illumination of the cell; in this instance the recording will be what is known as "positive" recording. The fixed equal resistors 29 and 30 are provided for the purpose of obtaining a fixed 10 centertap for the resistance arms of the bridge 15, said centertap being connected through a load-resistor 31 to the control grid of the first amplifier stage 33.

The bridge 15 further comprises capacitance 15 arms connected across the outer terminals of the resistors 26 and 28 respectively, which comprise the inter-electrode capacities of the photocell electrodes and an external balancing condenser 35. The bridge 15 as described in greater detail 20 in the prior patent of W. P. Asten, above-mentioned, may be balanced for any desired level of illumination of the cell by adjustment of the potentiometer 27. A further phase-shift compensating network comprising resistors 36, 37 25 and 38 and a condenser 39 is preferably connected in shunt relation to the resistance arms of the bridge, this feature being disclosed and claimed in said prior patent.

Fig. 5 is a schematic diagram illustrating the 30 relation of the reversely-connected cathodes of the photocell to the alternating source 16 and the output circuit 17. It will be evident that by means of the novel connection of the dual cathode photocell 13 to the bridge network 15, the two reversely-connected cathodes 19, when equally illuminated by the light reflected from the copy on the drum 10, become alternately operative to produce a current flow in the output circuit 17 upon alternate half-cycles of the carrier from the source 16 of alternating electromotive force. When one cathode is positive with respect to its associated anode, the other cathode being oppositely connected to the source 16 and bridge network becomes conducting, and generates an output current which is a function of the illumination of the cell. On the next half-cycle or reversal of current from the source 16, the other pair of electrodes 19 and 20 of the photocell become operative.

The improved modulating method can be explained with reference to the curves of Figs. 6 and 7. If it is assumed that only one cathode of the photocell 13 is illuminated, or a conventional single-cathode photocell were used, the current through the photocell would be as shown at 41 in Fig. 6, at a predetermined level of illumination of the photocell. The current builds up in one direction only to a maximum value, because of the unilateral conductivity of the cell, whether such a cell is employed with a chepper wheel or in a bridge circuit having an applied carrier voltage. To illustrate operation under varying light conditions, the output current would be as indicated by the curve 42 where the illumination of the cell is momentarily increased. It will be apparent that the output current contains a direct-current component which changes the potential bias of the control grid of the amplifier 33. This causes distortion of the signal wave train in the output of the amplifier, as is well understood to those skilled in the art, and various expedients such as filtering have been employed to reduce the distortion. In accordance with the invention the distortion is eliminated by causing a current flow through the cell upon

both half cycles of the applied electromotive force as indicated by the curve 43 in Fig. 7, by interconnecting the cathodes and anodes of the photo-cell so that each pair of electrodes is operative on each succeeding half-cycle of current. The resulting output current where the bridge network is employed is represented by the curve 44 in Fig. 7. It will be apparent that the signal wave produced is a modulated alternating current without any direct-current component. Such a signal can be amplified in a conventional vacuum-tube amplifier without distortion. In actual practice it is found that the distortion in transmission is reduced and improved recording can be effected when the described modulating method is employed.

In order to avoid the loss of light projected through the space between the two cathodes of the #920 photocell, a split prism or optical wedge 46 can be arranged in front of the cell as shown in Fig. 3, or with two separate cells of the single-cathode type. The wedge 46 consists of two prisms with their edges abutting at the center of the beam of light reflected from the copy as shown, whereby half the light is directed to the active surface of each cathode. Other equivalent optical elements may be employed in a similar manner instead of the wedge 46. Another preferred form of photocell modulator embodying the invention is shown in Fig. 4. In this modification, the balanced bridge and amplifier are connected to the photocell 48 in the same manner as shown in Fig. 1 except that the photocell is provided with a third anode 49 disposed behind the cathodes of the cell and the condenser 35 is omitted. The capacity between the electrode 49 and the cathodes of the photocell balances the capacity between the other electrodes 20 and the cathodes, and thus no external condenser 35 is required. The advantage of this construction is that the elements of the capacity represented by the electrode 49 and the cathodes 19 are sealed inside of the photocell envelope and are thus not affected by moisture and the like. However, the anode must be accurately positioned so that the proper interelectrode capacity is obtained. Since the operation of the modulator shown in this figure is the same as that shown in Fig. 1, no further explanation thereof is deemed necessary.

In some applications the anodes 20 are unnecessary since each cathode could function as an anode during the half-cycle when the other cathode is at a negative potential. A photocell 51 of this type is illustrated in Fig. 8. As shown, the photocell 51 comprises two photo-electric cathodes 52 and 53, arranged substantially perpendicular to each other and overlapping so that no light from the source or scanning spot 54 escapes between the cathodes. A two-part balancing electrode insulated to prevent space current and consisting of wires or rods 55 and 56, one mounted behind each of the respective cathodes, is provided for the purpose of obtaining a capacity balance when the cell is used with a bridge network of the type shown in Figs. 1 and 4. The total capacity between the electrode 55, 56 and cathodes 52 and 53, is equal to the capacity between the two cathodes. Preferably the parts of the electrode 55, 56 which are adjacent the cathodes or exposed to electron emission there-

from, are covered or coated with insulation as indicated, to obviate the flow of electron current to this electrode. The cathodes 52 and 53 may be connected, for example, in the same manner as the cathodes of the photocell 48.

While several embodiments of the invention have been described by way of example, other modifications will occur to those skilled in the art and may be made without departing from the scope of the invention. For example, in certain applications separate photocells may be employed instead of a single photocell provided with a plurality of photo-electric cathodes, although the latter modification is usually preferable.

15 I claim:

1. In a photocell modulator, in combination, a photocell provided with electrodes including two photo-electric cathodes and an anode, an output circuit for said photocell, said circuit including one of said cathodes, a source of alternating electromotive force and means comprising a balancing network connected between said source and said output circuit for generating a modulated carrier in said output circuit upon equal light modulation of both of said cathodes, said network including the space paths between electrodes of said photocell and also including external impedances connected to said source and the electrodes of said photocell.
- 20 2. In a photocell modulator, in combination, a photocell provided with two separate photo-electric cathodes and a balancing electrode in spaced relation to said cathodes, a balanced bridge network including said photocell in one arm thereof, a carrier-current source connected to opposite terminals of the bridge network, an output circuit associated with said photocell and bridge network, means to illuminate the cathodes of the cell equally with light varying in a predetermined manner and connections for said cathodes to render each operative to establish current flow in an area of the bridge on alternate half-cycles of said carrier-current source.
- 25 3. In a photocell modulator, in combination, a photocell provided with two separate photo-electric cathodes and a balancing electrode in spaced relation to said cathodes, a source of carrier current, a balancing network connected to said source and comprising the space paths between said electrodes of the photocell, means including said source for rendering said cathodes alternately operative to establish current flow to the other cathode as an anode at a relatively positive potential on alternate half-cycles of said carrier-current source and means to apply light excitation equally to said cathodes.

JOHN R. SHONNARD.
